UNITED STATES PATENT OFFICE.

EMIL F. HOLINGER, OF NEW YORK, N. Y., ASSIGNOR TO E. CHASE CROWLEY, OF NEW YORK, N. Y.

ANTICREEPING DEVICE FOR RAILWAY RAILS.

Application filed December 11, 1926. Serial No. 154,123.

The invention relates to anticreeping devices in which a rolling member interposed between the edge of the base-flange of the rail and a fixed adjacent surface on the tie-plate is engaged or cramped between such edge and surface by the movement of the rail relatively to the tie-plate, and it relates more particularly to a structure in which the rolling member thus cramped is in the form of an elliptical roller.

The object of the invention is to provide means for positively but movably engaging the roller with the tie-plate and thus avoiding the danger of the roller slipping or sliding relatively to such fixed surface and thereby insuring the proper presentation of the roller in effecting the desired grip on the rail in all positions of the latter.

The invention consists in certain novel features of construction and arrangement by which the above and other objects are attained to be hereinafter described and claimed.

The accompanying drawings form a part of this specification and show an approved form of the invention.

Figure 1 is a plan view showing a position of a rail supported upon and engaged with the improved tie-plate and roller.

Figure 2 is a corresponding vertical section taken on the line 2-2 in Figure 1.

Figure 3 is a plan view of the roller and a position of the tie-plate, on a larger scale.

Similar reference numerals indicate the same parts in all the figures.

The rail is of standard type having a head 5, vertical web 6 and base-flanges 7 and 8, supported on a tie-plate 9 and held in place thereon and to the tie, not shown, by spikes 10 in any approved manner.

On the upper face of the tie-plate, near one end, is a transverse abutment 11 extending parallel with the outer base-flange 7 serving to hold the rail against outward lateral movement, and on the upper face of the tie-plate, oppositely disposed to the abutment 11 and separated from the inner base-flange 8, is a ridge 12 having vertical teeth 13 constituting a rack extending parallel with the edge of the base-flange 8.

The rolling member 14 lies in the space between the rack 13 and edge of the base-flange 8, and is elliptical in plan with its periphery perpendicular to its base and is formed with vertical gear-teeth 16 adapted

to mesh with the teeth of the rack 13. It is preferably of steel harder than the rail so that its teeth 16 will bite slightly into the edge of the base-flange 8 under sufficient pressure and thus engage strongly with such edge.

The minor diameter of the outer periphery of the toothed roller 13 is the same, or preferably slightly greater than the width of the space between the base-flange 8 and the roots of the teeth 13 of the rack, and the roller is inserted in such space by engaging its teeth with the rack and also frictionally with the edge of the base-flange 8; it is then driven by blows of a hammer until its under face contacts with the upper face of the tie-plate.

Thus engaged the longitudinal movement of the rail causes the frictional bite or pinching action to increase as the angle of the major diameter of the ellipse widens relatively to the rack 13 and edge 8, with the result that the movement of the rail is effectively checked when the roller has travelled a short distance.

By the engagement of the teeth of the roller with the teeth of the rack the roller is compelled to make the partial rotation required to effect the pinching action and the danger of slipping or sliding movements of the roller relatively to the ridge 12 is eliminated. The engagement also insures that a reverse movement of the rail returns the roller first to the original position and then moves it positively into position to resist a further movement in such reverse direction.

The points of the teeth 16 of the roller and also the angles at the roots are preferably rounded as shown to lessen the danger of fracture under the excessive strains to which the teeth are subjected. The teeth 13 of the rack are similarly shaped for the same reason.

The teeth on the rolling member and the corresponding teeth of the rack may be varied in proportions as may be found necessary or desirable in adapting the invention to various conditions of service.

I claim:

1. In an anticreeping device a tie-plate adapted to support a rail, an abutment on said plate adapted to be against the outer base-flange of said rail, a serrated ridge on said plate adjacent to and separated from the inner base-flange of said rail, and a

toothed rolling member located in the space between said inner base-flange and said ridge, in mesh with such serrations and adapted to engage frictionally with said inner base-flange and to increase such frictional gripping action by the movement of said rail longitudinally.

2. In an anticreeping device, a tie-plate adapted to support a rail, an abutment on said plate adapted to lie against the outer base-flange of said rail, a ridge on said plate adjacent to and separated from the inner base-flange of said rail, said ridge having teeth presented toward the inner base-flange and forming a rack parallel therewith, and a toothed rolling member located in the space between said inner base-flange and said ridge, in mesh with said rack and adapted to engage frictionally with said

inner base-flange, and to increase such frictional gripping action by the movement of said rail longitudinally. 20

3. In an anticreeping device, a tie-plate adapted to support a rail, an abutment on said plate adapted to lie against the outer base-flange of said rail, a ridge on said plate adjacent to and separated from the inner base-flange of said rail, said ridge having teeth presented toward said inner base-flange and forming a rack parallel therewith, and a toothed elliptical rolling member located in the space between said inner base-flange and said rack in mesh with the latter, and adapted to engage frictionally with said inner base-flange. 25 30 35

In testimony that I claim the invention above set forth, I affix my signature hereto.

EMIL F. HOLINGER.
